CLAIM

The ornamental design for a napkin and wrap, as shown and described.

DESCRIPTION

FIG. 1 is a frontal perspective view taken from the right side and above a napkin and wrap showing my new design;

FIG. 2 is a top plan view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a bottom plan view thereof; and,

FIG. 8 is a perspective view of the napkin and wrap wrapped around the neck of a seated person, shown in broken lines, illustrating a use of the new design. The broken line showing of environment is for illustrative purposes only and forms no part of the claimed design.
